H. G. GILLMOR.
ANTICREEPER FOR RAILS.
APPLICATION FILED DEC. 6, 1915.

1,268,958.

Patented June 11, 1918

UNITED STATES PATENT OFFICE.

HORATIO G. GILLMOR, OF WASHINGTON, DISTRICT OF COLUMBIA.

ANTICREEPER FOR RAILS.

1,268,958.

Specification of Letters Patent. Patented June 11, 1918.

Application filed December 6, 1915. Serial No. 65,242.

To all whom it may concern:

Be it known that I, HORATIO G. GILLMOR, a citizen of the United States, residing at Washington, in the District of Columbia, have invented certain new and useful Improvements in Anticreepers for Rails, of which the following is a specification.

The object of my invention is to provide a novel, simple and efficient device, which when applied to the rail will prevent the longitudinal displacement or creeping thereof.

Other objects of the invention are to provide a device which may readily be applied with the tools usually in the hands of the men employed upon track and which while it may readily be removed with the same tools cannot be accidentally loosened or displaced.

The device possesses other features of novelty and advantage, which, with the foregoing, will be obvious from the following description.

One form of embodiment of the invention is shown in the accompanying drawings, in which:

Figure 1 is a plan view showing the device in operative position on the rail.

Fig. 2 is a sectional view at the plane indicated by the line X-X in Fig. 1.

Fig. 3 is a sectional view, at the same plane, showing a position of the anticreeper when being applied to the rail.

Fig. 4 is a side elevation showing the device in position.

Similar letters refer to similar parts throughout the several views. In the form of the invention illustrated in the drawing, A represents the rail resting upon ties or sleepers, a portion of one of which is shown at B. The rail A is of the usual construction, comprising a head or tread portion C and a base flange D. Engaged with the rail A and the crosstie B is the anticreeper E.

The anticreeper E is provided at one side of the rail with a jaw F, formed by overturning a portion G of the bar of which the anticreeper is constructed. At the other side of the rail A is a part H, which extends between and engages with the bottom of the rail head C and the top of the base flange D. Extending outwardly from the lower portion of the part H and over the top of the base flange D is a part I, from which depends a part K, which connects the jaw F and the parts H and I beneath the base flange D and provides a tie engaging part

of the anticreeper E engaging with the tie B. The upper portion of the part H may be turned or set as at L and there will then be exposed an end M facing outwardly from the rail.

In applying the anticreeper to the rail, E is placed with the part K transverse to the rail with the jaw F engaging the rail base flange D at one side of the rail, as illustrated in Fig. 3. The form and relation of the parts H and I are such that, in this position of the device, I will engage with the top edge of the base flange D opposite the jaw F at the other side of the rail and the upper portion of the part H will just begin to engage the outer portion of the underside of the rail head C all as clearly shown in Fig. 3. When the device is in this position, by striking the device at M the upper portion of the part H is driven toward the rail A, its top engaged and held by the under side of the rail head C. The part H is by this action caused to move angularly and at the same time move downwardly. This action causes the part L to fulcrum upon the upper edge of the base flange D and to transmit to the jaw F a transverse pull through the connecting portion K of E. It will thus be readily understood that when the device has in this manner been driven to the operative position shown in Figs. 1, 2 and 4, the part H is firmly wedged in between the bottom of the head C and the top of the base D of the rail; the part I is pressed firmly down upon the top of the base flange D and the jaw F drawn transversely of the rail; so as to grip the base flange D at that side of the rail. The rail A is in this manner firmly gripped by the anticreeper E and if longitudinal movement of the rail occurs the anticreeper E will be carried forward with the rail until the part K comes into contact with the crosstie B. The engaging of the crosstie B by the part K of the anticreeper E will prevent further movement of the rail in relation to the tie B.

To remove the device from the rail, it will be necessary first to force the upper portion of the part H outward from the rail to the position shown in Fig. 3 and when the device is in this position disengage the jaw F from the base flange D and remove the device from the rail.

It will be readily understood that the device is effectually locked in place upon the rail when the part H has been driven to the

operative position. In this position of the parts the part H is subject to stresses tending to cause it to move vertically. The engagement of the upper portion of H with the bottom of the rail head C prevents this vertical movement and effectually locks the device in position.

While I have described my invention as embodied in the construction shown in the drawings, modifications might be made without departure from the principles of the invention. Therefore, I do not wish to be understood as limiting the invention to the particular construction, arrangement and device shown and described except so far as these limitations are specifically set forth in certain claims herein.

I claim and desire to secure by Letters Patent:

20. 1. An anticreeper for rails, comprising a transversely extending bar provided with means for engaging one edge of a rail base flange and means at the other end thereof engaging the under surface of the head and the upper surface of the base flange and arranged to be driven in between said head and said base flange by a forced transverse angular movement in relation to the rail.

2. The combination, with a crosstie and a railroad rail having a head and a base flange, of an anticreeper provided with a part arranged to be forced in between the bottom of the rail head and the top of the base flange of the rail by forced angular movement of said part transversely in relation to the rail, and means engaged with the tie preventing movement of the lower portion of said part.

3. A rail anchor, comprising a transverse bar, means at one end of said bar for engaging the edge of the rail base at one side of the rail, means at the other end of said bar for engaging the under side of the head and the upper side of the base flange of the rail, said base flange and head engaging means being arranged to be forced into position by forced angular movement thereof transversely in relation to the rail.

4. The combination, with a crosstie and a railroad rail having a head and a base flange, of an anticreeper provided with a part engaged with the bottom of the rail head and the top of the base flange, and means engaging with the tie and preventing forward movement of said part, said part being arranged to be forced into position by driving the rail head engaging portion thereof toward the rail.

5. A rail stay, comprising a transverse part adapted to extend under the base flange of a rail and provided with means for engaging the edge of the base flange at one side of the rail and means for engaging the head and upper surface of the base flange of the rail at the other side of the

70 rail, said head and base flange engaging means being so arranged that, with said base flange edge engaging means in engagement with the edge of the rail base flange, said head and base flange engaging means may, by forced transverse angular movement thereof toward the rail, be engaged with the rail head and base flange and the gripping action of the device thereby secured.

6. In a rail anchor, a body having a portion disposed so as to engage a fixed portion of the roadbed in opposition to the tendency of the rail to creep, a jaw at one end adapted to engage the rail base at one side of the rail, an arm adapted to engage the top of the rail base at the other side of the rail and a vertically extending rail head engaging part, all so disposed as to cause said jaw and said arm to rigidly engage the rail base 85 when said part is forcibly moved transversely of the rail in engagement with the rail head.

7. A rail anchor, comprising a transverse bar provided with a rail base edge engaging jaw at one end thereof and, at the other end thereof, a portion adapted to engage the upper corner of the opposite edge of the rail base and, fulcrumed upon said corner of the rail edge, to be forced transversely 90 into engagement with the head and upper surface of the base flange of the rail, whereby a transverse pull is put upon said bar and pressure exerted upwardly on the head and downwardly on the base of the rail.

8. An anticreeper constructed with a transverse bar provided with a rail base edge engaging means at one end thereof and at the other end thereof a portion adapted to engage the rail head and rail base flange 105 and, by a camming action between said portion and the rail head when driven transversely of the rail and in the direction of the rail base edge engaging means, to effect the gripping action of the device upon the rail.

9. A rail anchor, comprising a transverse bar provided with a jaw at one end adapted to engage the rail base edge and a portion at the other end thereof arranged to effect 115 the gripping action of the device and lock the same in position by being driven transversely toward and under the rail head.

10. A rail stay, comprising a transverse bar provided with means for engaging the 120 edge of the base flange of the rail at one side and an integral vertically extending part of the opposite side arranged to be forced into engagement with the head and base flange of the rail by a transverse angular movement of said vertically extending part in relation to the rail.

11. The combination, with a crosstie and a railroad rail having a head and a base flange, of an anticreeper provided with a 130

- part engaged with the bottom of the head and top of the base flange of the rail and a transverse part projecting from said part first named engaging the cross tie and one side only of the rail base flange, said anticreeper being locked in position by pressure exerted upon the rail head by said anticreeper intending to resume a position from which it was sprung.
12. The combination, with a crosstie and a railroad rail having a head and a base flange, of an anticreeper comprising a transverse bar provided with means for engaging one edge of a rail base flange and means operative upon the other end of said bar to subject said bar to a transverse pull and to lock said anticreeper in position by an upward pressure upon the under side of the rail head.
13. An anticreeper, including a body member adapted to engage a cross tie, a terminal gripping jaw adapted to engage the rail base at one side of the rail, an arm adapted to engage the upper surface of the rail base at the other side of the rail and a rail head engaging part connected with said arm, said rail head engaging part being adapted to be moved transversely of the rail after said jaw and arm are brought into engagement with the rail base, whereby said jaw and arm may be tightened or loosened on the rail base.
14. A rail anchor, comprising a bar adapted to extend under the base flange of the rail and formed at one end with a jaw which is substantially horizontal and at the other end with a portion which engages only the upper surface of the base flange and the under surface of the rail head opposite to said jaw.
15. An anticreeper formed of a single bar of metal bent to form a jaw adapted to engage the rail base at one side of the rail, an arm adapted to engage the top of the rail base at the opposite side of the rail and a rail head engaging member adapted to be forced, by transverse angular movement, into engagement with the rail head.
16. An anticreeper, comprising a member having ends thereof bent to form a body portion, a jaw for engaging the top and bottom of the base flange at one side of the rail and a portion for engaging the under side of the head and the top of the base flange at the other side of the rail, said rail head and base flange engaging portion being so disposed with relation to said body portion and jaw as to necessitate distortion thereof to allow engagement with the rail head.
17. A rail anchor, comprising a member adapted to extend under the rail and provided with portions adapted to engage the rail base at opposite sides of the rail, one of said base engaging portions being provided with a rail head engaging extension adapted to be forced transversely angularly into engagement with the rail head whereby the device is subjected to strain when applied.
18. A rail anchor, comprising a member adapted to engage the under side of the head and the upper surface of the base flange of the rail at one side thereof and extend under the rail and engage the edge of the base flange at the other side thereof which, when applied to said rail is subjected to a bending strain which produces a transverse gripping of the opposite sides of the rail base.
19. An anticreeper, comprising a member having ends thereof bent to form a body portion and end jaws for engaging the upper surfaces of the rail base, one of said jaws being extended upwardly to provide a rail head engaging portion so disposed as to necessitate distortion of said anticreeper after being placed upon the rail to effect the engagement of the rail head engaging portion with the rail head.
20. A device for preventing the creeping of rails, comprising a bar of resilient metal provided at one end with a jaw and at the other end with a rail head and base flange engaging portion, said bar being formed with a bend whereby when the rail head and base flange engaging portion are forced in between the head and base of the rail the jaw is drawn transversely of the rail and the device caused to grip the rail.
21. A rail anchor, comprising a bar adapted to extend under the base flange of the rail and engage the edge of the same at one side and the upper surface of the same at the other side of the rail and provided with a resilient rail head engaging extension formed so as to be strained when forced into engagement with the rail head.
22. A device for preventing the creeping of rails, comprising a bar adapted to extend under the base flange of the rail, formed with a jaw which engages the upper and under surface of the base flange at one side of the rail and an arm which engages the upper surface of the base flange at the other side of the rail and is provided with a resilient rail head engaging extension formed so that it is strained when forced into engagement with the rail head.
23. In an anticreeper, a body having at one end a jaw arranged to engage the edge of the rail base at one side of the rail and at the other end a portion disposed so as to rigidly engage the upper surface of the base flange and the under surface of the rail head when said portion is forcibly moved transversely angularly about the rail base and thereby retain the anticreeper in position on the rail.

H. G. GILLMOR.
